United States Patent Office.

JOSEPH L. CHAPMAN, OF PHILADELPHIA, PENNSYLVANIA.

Letters Patent No. 81,600, dated September 1, 1868.

IMPROVEMENT IN ROLLING-MILLS.

The Schedule referred to in these Letters Patent and making part of the same.

TO ALL WHOM IT MAY CONCERN:

Be it known that I, JOSEPH L. CHAPMAN, of the city and county of Philadelphia, and State of Pennsylvania, have invented a new and useful Improvement in Round-Bar-Rolling Mills; and I do hereby declare that the following is a full and exact description thereof, reference being had to the accompanying drawings, and to the letters of reference marked thereon.

The nature of my invention mainly consists in the combination and arrangement of three rollers in relation to each other, in such a manner as to form a space between them at one end of sufficient size to receive the largest pile to be pressed into a rod, and of the proper distance apart, so that when the said pile shall be delivered through the space between the rollers at their other ends, by the revolution of the same, it shall be compressed into the requisite size for the rod. It also consists in placing the rollers on a twist or slight angle with each other, so as to cause the pile to advance to the delivery-end as the rollers revolve.

It further consists in making the rollers larger at their receiving than at their delivery-end, so as to make the relative velocity of their periphery at each end coincide with the relative velocity of the pile and the rod, to prevent giving twist to the latter.

It further consists in combining the rollers at their receiving-end by means of ball-and-socket joint with the housen, and making them adjustable at their other end by set-screws, or other mechanical equivalent, for the purpose of adjusting them at their delivery-end, to form rods of various sizes.

In the accompanying drawings, which form a part of this specification—

Figure 1 is a plan or top view of the mill.

Figure 2 is a side elevation of the same.

Figure 3 is an end elevation of the receiving-end of the mill.

Figure 4 is a like view of the delivery-end of the same.

Figure 5 is a face view of one of the rollers C' and box b'.

Like letters in all the figures indicate the same parts.

A is the bed-plate of the mill; B and B' are the housens; C, C', and C' are rollers, which are connected with the housen B by means of ball-and-socket joints. The housen B has a cap-piece, D, confined thereto by screw-bolts a. The joints in the housen and cap are seen in fig. 1. The rollers are connected with the housen B' by means of their journal-boxes b, b', and b'. The box b is stationary, but b' b' are adjustable in the slots c' and c', there being adjusting-screw bolts E E, which are tapped into the housen. There are bolts F F, whose eyes d, encircle the round part e of the boxes. The bolts pass through the permanent lugs f f of the housen, and have a nut on their ends, between which, and their respective lugs, there is a cylindrical spring, g, to draw the box against the set-screw bolts E E.

The said rollers C, C', and C' have pinions G on their receiving-end, which gear into the central wheel H, on the inner end of the hollow shaft I, through which the pile is passed to enter the space between the rollers. The said shaft has its bearing in the housen B. The teeth of the wheel H have a twist corresponding to the twist position of the rollers.

I make the rollers C, C', and C' larger at their receiving than at their delivery-end, so that their velocity at each end will correspond with the respective circumferences of the pile and the size of the finished rod.

The small ends of the rollers should be rounded off on the corner to prevent their cutting into or marking the rod.

The set-screws E E are adjusted to vary the size of the rods.

It will readily be seen that rods of various sizes may be formed in the same mill by adjusting the rollers, and that they are necessarily made of regular diameter at one operation. Heretofore the rods were formed by passing the pile between cross-grooves of rollers, and repeating the operation several times with the rods, to bring them to their proper size, and make them round. And after all, there has been found great difficulty in making the rods round.

J is a pulley on the outer end of the hollow shaft I, which communicates, by means of a belt, with the motive-power.

What I claim as my invention, and desire to secure by Letters Patent, is—

1. The arrangement of three smooth conical rollers, rotating in different planes, and operating in the manner described, to form and feed the rod simultaneously, as above specified.

2. The adjustment of the rollers C' C', to form rods of different sizes, by means of ball-and-socket joints at one end, and set-screws and journal-boxes at the other end, substantially in the manner shown and set forth.

In testimony that the above is my invention, I have hereunto set my hand, and affixed my seal, this 29th day of June, 1868.

JOS. L. CHAPMAN. [L. S.]
